AUTOMATIC LOOM SHUTTLE

James Gardiner Allen, Hopedale, Mass., assignor
to Draper Corporation, Hopedale, Mass., a cor-
poration of Maine

Application September 26, 1942, Serial No. 459,795

4 Claims. (Cl. 139—223)

The present invention relates to automatically threading shuttles for looms and, as illustrated herein, relates more particularly to means for trapping the thread so that the shuttle will not become unthreaded.

In weaving with automatic looms of the filling replenishing type, it is usual to provide a series of filling carriers having filling wound thereon and contained in a hopper or other suitable supply means, such for example, as a rotatable carrier. The end of the filling is usually secured to some fixed part so that the shuttle on the first pick following replenishment will become partially threaded and on the next or return pick the shuttle will become completely threaded. Under some conditions during the weaving operation, the filling thread may be thrown out of the thread passage in the thread block and the shuttle may thus become completely unthreaded. This is objectionable since it usually results in breaking the filling thread and, since the break usually occurs after the shuttle has entered the shed, the filling will break in the shed and a short pick will be woven into the cloth. This short pick must be removed and, since the loom must be stopped, loss of production results.

In order to insure that the shuttle will be partially threaded during the first pick following replenishment, some shuttles are provided with threading blocks having a substantially straight thread guiding groove or passage wherein in the rear wall of the thread block recess forms one wall of the thread groove and the other wall of the thread guiding groove is formed by rear wall of the block itself. These eyes are not entirely satisfactory since the groove varies in width in accordance with atmospheric conditions. Such grooves must be made sufficiently wide so that they will not close up even under the most extreme conditions. Such an eye will unthread relatively easily. To avoid this condition, threading blocks have been provided having an obstruction in the threading groove which will prevent unthreading thereof but such blocks are objectionable since they are difficult to thread and hence may not become threaded even partially during the first pick after replenishment.

One object of the present invention is to provide an automatically threading shuttle which will overcome the above mentioned difficulties. To this end, the threading block is provided with a threading passage or groove which is substantially straight and unobstructed and which will remain substantially constant in width under all

conditions and which is provided with a thread trap close to its outer end. In the illustrated embodiment of the invention, the outer end of the threading groove in the block terminates rearwardly of the outer end wall of the block receiving recess to provide an effective and satisfactory thread trap which will prevent unthreading of the shuttle.

Another object of the invention is to improve generally on the construction and operation of automatically threading shuttles. To this end, the threading block is formed without any overhanging or overlapping parts which would require bending into position. As a result, manufacture of the block is facilitated and less expensive metals, such, for example, as cast iron, can be used while at the same time providing a thread block which operates more certainly than prior blocks both in ease of threading and freedom from unthreading.

With the above and other objects and features in view, the invention will be described with reference to the accompanying drawing which illustrates a preferred embodiment of the invention and in which—

Fig. 1 is a plan view of the outer end of an automatically threading shuttle embodying the present invention;

Fig. 2 is a view in cross section taken along the line II—II of Fig. 1;

Fig. 3 is a view in end elevation of the threading block looking toward the inner end thereof;

Fig. 4 is a view in front elevation of the threading block;

Fig. 5 is view similar to Fig. 1 but showing the shuttle partially threaded prior to the end of the first pick of the shuttle; and

Fig. 6 is a view in front elevation of the shuttle shown in Fig. 1;

Fig. 7 is a view in section taken along the line VII—VII of Fig. 5.

The shuttle illustrated in the drawing comprises a shuttle body 2 provided with a longitudinal cavity 4 in which a filling carrier such, for example, as a bobbin 6, is releasably held in the cavity 4 by any suitable means (not shown) to permit automatic replacing of the bobbin when the filling F thereon has become substantially exhausted.

The shuttle body 2 is recessed at 8 to receive a threading block 10. The recess 8 includes a front wall 11, a rear wall 12 and an outer end wall 14. The front wall 11 and the rear wall 12 are substantially parallel to each other and to the longitudinal axis of the shuttle body 2. The

front wall of the shuttle body is cut away at 16 to provide for a side delivery eye. The body is also provided with a thread guiding groove 17 which extends outwardly and forwardly to the point of the shuttle and has a curved surface which intersects the outer end wall of the recess 8.

The threading block 10 is preferably made of metal and comprises a base portion 18 having upwardly extending side walls 20 and 22. A thread passage 24, is located in the base 18 between the side walls thereof and has a slot 26 in its top portion which extends longitudinally of the shuttle. Above the thread passage 24 and the slot 26, the rear side wall 20 is concaved longitudinally to form a rear thread guiding wall 28 for guiding the filling thread F into and through the slot 26 and into the thread passage 24. The front wall 22 is similarly shaped at 30 to form a guide wall for the filling thread F.

The entrance or inner end of the threading block 10 is provided with a pair of friction members or tension pads 32 of well known construction which are yieldingly urged into contact with each other by adjustable springs (not shown) and receive between them the filling thread F and tension the filling thread.

The front guide wall 22 is preferably concaved and rounded to form an outwardly directed hook 34 adjacent to the outer end of the slot 26 which is effective to direct the filling thread F laterally away from the slot 26 if the shuttle becomes partially unthreaded.

The construction described above is old and well known in the art and need not be described further herein.

The outer end of the rear wall 20 of the threading block 10 is substantially straight and terminates at the outer wall 14 of the threading block recess 8 and rearwardly of the groove 17. The forward face 36 of the rear wall 20 is inclined slightly downwardly and rearwardly as best shown in Fig. 2 of the drawing and is located rearwardly of the forward edge of the outer end wall 14 of the threading block recess 8. As illustrated best in Fig. 2, the entire forward face 36 is located rearwardly of said forward edge but it is apparent that, if so desired, only the lower portion thereof need be so located.

The front wall 22 of the block 10 is extended outwardly to constitute a horn 38 which at its outer end portion is provided with an inclined rear face which is spaced from and parallel to the forward face 36 of the rear wall 20 of the threading block 10. The slot 40 formed between the horn 38 and the forward face 36 of the rear wall 20 is inclined downwardly and rearwardly and the slot 40, except at the upper end portion thereof, is located rearwardly of the forward edge of the outer end wall 14 of the recess 8. Thus, at least, the lower end portion of said slot is located rearwardly of said forward edge to form an effective thread trap which will prevent unthreading of the shuttle.

With the above construction, a threading slot comprising the slots 26 and 40 is provided, which is unobstructed from its inner end adjacent to the tension pads 32 to its extreme outer end, thus providing a threading block which is easily threaded. Because of the location of the lower end portion of the outer end of the slot 40 rearwardly of the forward edge of the outer end wall 14 of the recess 8, the shuttle cannot unthread after the first pick. The trap formed by the outer end wall 14 will prevent the filling from lift-

ing upwardly by reason of a kink or twist in the filling yarn as it becomes loose or slackened when the shuttle is boxed at the end of the first pick and the lay moves forwardly. Thus the partially threaded shuttle cannot become unthreaded.

During the second pick the shuttle moves in the opposite direction and the filling F is pulled forwardly and under a depending horn 42 and passes out through the opening 16 formed in the front wall of the shuttle 2. It is apparent from the above, that the filling thread F is effectively trapped not only at the juncture of the wall 14 and the outer end of the slot 36 but is also trapped by the depending horn 42. Thus the shuttle 2 cannot become unthreaded after the shuttle has been either partially or completely threaded.

While the illustrated embodiment of the invention has been found to be a practical form, it is evident that variations may be made in the threading block and in the shuttle itself without departing from the spirit of the present invention.

Having thus described my invention, what I claim as new and desire to secure by Letters Patent of the United States is:

1. An automatically threading loom shuttle comprising a shuttle body having a cavity therein for receiving a filling carrier, a threading block fixed in a recess formed outwardly of the cavity in said shuttle body, said threading block having a longitudinal thread passage communicating with said cavity, said shuttle body having a longitudinal thread groove extending outwardly and forwardly from said recess, said threading block having a horn which projects outwardly from the threading block and has a rearwardly inclined surface, the lower rearward end portion of which surface terminates close to and behind the outer end wall of the block receiving recess, and a rear member having a surface parallel to and cooperating with said inclined surface on the horn to form a thread receiving slot, the lower rearward end portion of said slot lying behind the outer end wall of the block receiving recess to form a thread trap to prevent unthreading of the shuttle.

2. An automatically threading loom shuttle comprising a shuttle body having a cavity there-in for receiving a filling carrier, a threading block fixed in a recess formed outwardly of the cavity in said shuttle body, said threading block having a longitudinal thread passage communicating with said cavity, said shuttle body having a longitudinal thread groove extending outwardly and forwardly from said recess, said threading block having a horn which projects from the threading block and having a flat rearwardly inclined surface, the lower rearward end of which surface terminates close to and behind the outer end wall of the block receiving recess and laterally of the longitudinal passage in the shuttle body, and a rear member having a surface parallel to and cooperating with said inclined surface on the horn to form a thread receiving slot, the lower rearward portion of said slot lying entirely behind the outer end wall of the block receiving recess to form a thread trap to prevent unthreading of the shuttle.

3. An automatically threading loom shuttle comprising a shuttle body having a cavity there-in for receiving a filling carrier, a threading block fixed in a recess formed outwardly of the cavity in said shuttle body, said threading block having a longitudinal thread passage communicating

with said cavity, said shuttle body having a longitudinal thread groove extending outwardly from said recess, said threading block having a horn which projects outwardly from the threading block and which is provided with a flat rearwardly and downwardly inclined surface, the rearward end portion of which terminates close to and behind the outer end wall of the block receiving recess, and a rear member having a forward end surface portion parallel to and cooperating with said inclined surface on the horn to form a thread receiving slot projected toward the front wall of the threading block recess at an angle to the longitudinal axis of the shuttle body to form a thread trap.

4. An automatically threading loom shuttle comprising a shuttle body having a cavity therein for receiving a filling carrier, a threading block fixed in a recess formed outwardly of the cavity in said shuttle body and having a side delivery eye, said threading block having a longitudinal

thread passage communicating with said cavity, said shuttle body having a longitudinal thread groove extending outwardly from said recess, said threading block having a horn projecting outwardly from the threading block and which is provided with a rearwardly and downwardly inclined surface the rear lower end of which terminates close to and behind the outer end wall of the block receiving recess and laterally away from the longitudinal passage in the shuttle body, and a side member having a forward surface parallel to and cooperating with said inclined surface on the horn to form a thread receiving slot inclined downwardly and away from the side delivery eye and projected toward the outer end wall of the threading block recess at an angle to the longitudinal axis of the shuttle body, said outer end wall of the recess cooperating with the forward end portion of said horn to form a thread trap to prevent unthreading of the shuttle.

20 JAMES GARDINER ALLEN.
